CASING FOR A WRITING INSTRUMENT

Peter L. Tailer, 323 E. 17th St., New York, N.Y. 10003

Filed Oct. 9, 1970, Ser. No. 25,415

Term of patent 14 years

Int. Cl. D19—06

U.S. Cl. D74—17 B

FIG. 1 is a front view of a casing for a writing instrument showing my new design;

FIG. 2 is a left side view, the right side being a mirror image thereof;

FIG. 3 is a top plan view; and

FIG. 4 is a bottom plan view rotated 180 degrees from FIG. 1.

I claim:

The ornamental design for a casing for a writing instrument, as shown.
